Application May 7, 1949, Serial No. 92,068

Claims priority, application Sweden May 15, 1948

4 Claims. (Cl. 340—258)

1

The present invention relates to apparatuses which indicate when an object penetrates into a certain area. The apparatus comprises an electronic tube high frequency generator which is connected to an antenna device in the said area. Penetration into the area by the object changes the capacity between the antenna and earth. The indicating device in such apparatuses usually consists of a relay which is connected in such a way that an alteration in the current through its winding takes place when the circuit is affected, for example, when its frequency or oscillation amplitude is changed.

An important field for the use of such apparatuses is the keeping of guard, especially burglar alarms. Up to the present, however, no such apparatus has been produced for practical use. This is a consequence of lack of stability. In alarm and guard devices, where the apparatus must work day after day without attention in an absolutely reliable manner, it is an indispensable condition that it shall be stable i. e. in the mains, independent of variations in temperature or in the power mains.

In the present invention the said antenna device, the high-frequency generator and a sensitive device for detecting capacity variations between the said antenna device and earth which forms a capacity between the antenna device and earth are isolated with an isolating material having a mainly constant dielectric constant for normal temperature variations.

Preferably the invention comprises an oscillating circuit, included in the high-frequency electronic tube generator, and connected in the customary manner between the grid and another electrode, preferably the cathode of an electronic tube. Characteristics of the invention are that the connecting elements to the grid side of the circuit are so arranged that their resulting capacity is mainly constant for normal variations of temperature and that the impedance between the earth side of the circuit and the earth is small compared to the impedance between the said earth side and the power mains. The manner in which both sides of the oscillating circuit must be connected up in order to attain full stability will be explained further with reference to the annexed figure which shows an example of construction according to the invention.

The electronic generator consists of an electronic tube E and an oscillating circuit L₁C in a three-point coupling of known type. To the grid circuit of the tube, via the condenser C₁ and the resistance R₁, the antenna A is connected in par-

allel as a feeler. In the anode circuit of the tube, a relay R, adjusted for its limiting position, is connected as an indicating device. The apparatus is fed from the A. C. mains V via a transformer T together with a rectifier L and a filter condenser C₄.

The diagram shown of the apparatus, which is known in principle, functions as follows:

If $L_2=L_3$ (the tapping point is in the middle of the coil L₁), the tension between the tube's E-grid and cathode is small when $C_1=C_3$ and R_1 —the radiation resistance of the antenna, so that oscillations are not produced. If C_1 is smaller than C_3 , no oscillations are produced either, because the oscillations which might be supposed to arise between the grid and the cathode are out of phase. When on the contrary C_1 is greater than C_3 , self-oscillations are produced which feed the antenna. By reason of heavy damping in the oscillating circuit, chiefly dependent on the resistance R₁ the degree of oscillation of the tube can be regulated at will, for example to half the maximum amplitude. This adjustment is made by means of the condenser C₁. The said elements 10 coil L₁, condensers C₁ and C₃ and the tube E form thus a high-frequency generator. When the tube is oscillating, it operates as a grid rectifying detector, i. e. the grid receives a negative potential in relation to the cathode. The value of this potential is dependent on the degree of oscillation attained by the tube, which oscillation in turn is dependent on the value of the capacity C₃. The negative potential of the grid causes the anode current to fall. The said high-frequency generator which includes the said rectifying device 15 forms a sensitive device, i. e., sensitive for variations of the capacity C₃.

As will be further shown, according to the invention, the connecting elements connected to the circuit L₁C, as well as the circuit itself, must be arranged in a special manner if the apparatus is to be stable. In this connection, the grid side of the circuit will be dealt with first.

A good apparatus will give indication of a variation of 0.1 mmf. or less in C₃, preferably 0.01 mmf. It should be clear from the diagram that if the capacity between the grid of the tube and the cathode or the grid and the anode varies, this will cause mainly the same change in current in the anode circuit of the tube as if a variation in capacity was produced between the antenna and the earth. In normal variations of temperature ($\pm 20^\circ$ C.), such a capacity variation is normal in electronic tubes. The electronic tube, therefore must be specially constructed for the pres-

ent purpose. A first measure to be taken is to construct the tubes with the least possible grid-anode and grid-cathode capacities. This is achieved, amongst other things, by taking out the grid terminal direct through the wall of the tube with the shortest possible leads not running parallel to the leads from other electrodes. Further, the electrodes in the tube must be fixed with material possessing a small heat-expansion coefficient, for example steatite or something similar. Special attention must also be paid to the connection between the grid and the antenna and to the antenna itself, so that a stable capacity is produced in the grid side of the circuit, not variable with changes of temperature and humidity. This naturally also applies to the oscillating circuit itself. A compensating device may alternatively be resorted to. With changes of temperature it must have such changes in capacity that the changes in capacity of the other elements connected to the grid circuit are compensated.

As for the earth side of the circuit, it is necessary for the impedance Z_1 of the element, for example the coupling condenser to earth which forms the capacity C_3 with the antenna, to have a small impedance. Since the distance between the earth connection J_2 of the apparatus and the earth J_1 of the antenna can usually be made small, a suitably small and stable impedance can be obtained on this connection also. On the other hand, the impedance between the earth side of the circuit and the mains must be high for high-frequencies. This is due to the fact that the impedance of the mains to the earth J_3 may vary considerably, and thereby the resulting influence which the earth of the mains exercises over Z_1 via Z_3 may vary, which in its turn affects the circuit L_1C and causes faulty indication. Z_3 consists in this case partly of the impedance of the apparatus to the mains and partly of the mains impedance to earth. The manner in which the impedance of the mains can be varied is clear from the figure. The mains leads are supposed to have a certain length, for example overhead leads, so that the impedance Z_3 can be arranged to come in series with the leads. If thereafter a load B_3 with relatively large capacity C_2 is connected to the earth, the impedance is naturally decreased between the mains side of the apparatus and the earth, which implies that Z_1 is more heavily shunted. When the apparatus is connected to the mains via a transformer with electrically separate primary and secondary windings, or even with an earthed screen between windings, a fairly high impedance is produced between the two windings. In the case of a so-called universal-current or D. C. apparatuses a suitable impedance coil is connected between the apparatus and the mains. This may be of the so-called anti-disturbance type. In order to obtain a sufficiently high impedance, several such anti-disturbance filters, with their component condensers if any, must be connected up.

The above will now be further illustrated by an example of a universal current apparatus. Let $C_3=50$ mmf. The sensitivity of the apparatus, i. e. the variation of C_3 under the influence of the relay=0.01 mmf. or 2×10^{-4} of C_3 . Z_1 is a condenser of 5000 mmf. The example shows that the same variation in the circuit as under the influence of the relay (0.01 mmf.) can be obtained if Z_1 varies by about 0.75 mmf. and that a variation of the impedance Z_2 between, for

example, a and 50,000 ohms may also cause the said variations in Z_1 . From this it follows that a particularly effective filter must be connected between the mains side of the apparatus and the mains and that Z_1 must be chosen of low value. The usual value of Z_1 ($C=5,000$ mmf.) is generally too small and must be increased to at least 10 times as much.

By connecting the transformer between the apparatus and the mains, there is obtained, in the known manner, an electrical separation of the apparatus from the mains. For this reason, the circuit L_1C can be connected to the earth lead J_2 through Z_1 which, in its turn, by means of a lead of low impedance shown as a dotted line, is brought forward to the antenna earth J_1 , whereby such a low-resistance connection is obtained between the earth points J_1 and J_2 that the transformer T 's capacity C_5 , which should be able to be maintained about 100 mmf. or even lower, constitutes a sufficient uncoupling between the mains and the apparatus. In all circumstances, the impedance between the earth side of the circuit and the mains should be one hundred times greater than the impedance between the same side of the circuit and the earth.

We claim:

1. Apparatus with means of mains feeding for the indication of the penetration of an object into a certain area comprising an antenna device in the said area, at least one body for insulating the said antenna device from earth, an electronic tube coupled partly as a high-frequency generator with an oscillating circuit coupled to earth by means of a coupling element, and partly as an amplifier with a condenser and a resistance in parallel connected on one side to the oscillating circuit and on the other side to the antenna device, the said condenser fixed so that the oscillation amplitude strongly depends on the size of the capacity between the antenna device and earth, the said coupling element having a small damping effect on high-frequency current compared with the damping effect to the earth of the means of mains feeding, and the said body having a substantially constant dielectric constant for normal variations of temperature and humidity.

2. Apparatus with means of mains feeding for the indication of the penetration of an object into a certain area comprising an antenna device in the said area, an electronic tube with cathode, grid and anode, said tube coupled partly as a high-frequency generator with an oscillating circuit and partly as an amplifier with a condenser and a resistance in parallel connected on one side to the oscillating circuit and on the other side to the antenna device and the control grid in the tube, the said oscillating circuit also coupled to the cathode and to earth, the said condenser fixed so that the oscillation amplitude strongly depends on the size of the capacity between the antenna means and earth, the said oscillating circuit being coupled to earth by means of a coupling element with small damping effect on high frequency current compared with the damping effect on the means of mains feeding, and insulating body for the control grid in the tube forming a capacity between the said grid and anode and cathode with less than 0.1 mmf. capacity variation for 20 degrees Celsius temperature variation in the tube.

3. Apparatus with means of mains feeding for the indication of the penetration of an object

into a certain area comprising an antenna device in the said area, at least one body for insulating the antenna device to earth, an electronic tube coupled partly as a high-frequency generator with an oscillating circuit and partly as an amplifier with cathode, anode and control grid, the said oscillating circuit comprising an inductance with a tapping point, a condenser and a resistance in parallel connected on one side to the grid and on the other side to one end of the inductance, the tapping point of the inductance being connected to the cathode and the other end of the inductance to earth, the antenna device also being connected to the grid, the said condenser fixed so that the oscillation amplitude strongly depends on the size of the capacity between the antenna device and earth, the said inductance being coupled to earth by means of a coupling element with small damping effect on high frequency current compared with the damping effect on the means of feeding and insulating material forming a capacity between the antenna device and earth having a mainly constant dielectric constant for normal temperature variation.

4. Apparatus with means of mains feeding for the indication of the penetration of an object into a certain area comprising an antenna device in the said area, an electronic tube coupled partly as a high-frequency generator with an oscillating circuit and partly as an amplifier with cathode, anode and control grid, the said oscillating circuit comprising an inductance with a tapping point, a condenser and a resistance in
